Charles R. Searle.

UNITED STATES PATENT OFFICE.

WILLIAM RUTAN, OF NEW YORK, N. Y., ASSIGNOR TO GILLIS & GEOGHEGAN, OF NEW YORK, N. Y., A FIRM.

MECHANISM FOR OPERATING HOISTWAY-DOORS.

1,170,193.

Specification of Letters Patent.

Patented Feb. 1, 1916.

Application filed April 28, 1915. Serial No. 24,424.

To all whom it may concern:

Be it known that I, WILLIAM RUTAN, a citizen of the United States, residing in the city of New York, borough of Queens, in the county of Queens and State of New York, have invented a certain new and useful Improvement in Mechanism for Operating Hoistway-Doors, of which the following is a specification.

10 The invention relates to means for opening and closing the doors of sidewalk hoistways, and is designed especially for service with hoisting apparatus installed in the hoistway for raising cans of ashes and like loads from the cellar to the sidewalk.

The object of the invention is to provide simple, easily installed and operated means whereby the elevation or upward extension of the hoisting apparatus above the sidewalk level will automatically open the doors and close them again when such hoisting apparatus is lowered.

The invention consists in certain novel features of construction and arrangement by which the above objects are attained, to be hereinafter described and claimed.

The accompanying drawings form a part of this specification and show the invention as it has been carried out in practice.

30 Figure 1 is an elevation of the door operating mechanism, the doors and portions of the hoistway being shown in vertical section, and certain portions of the hoisting apparatus omitted. Fig. 2 is a corresponding vertical section, partly in elevation, taken on the line 2-2 in Fig. 1 and seen in the direction indicated by the arrows. Fig. 3 is a corresponding plan view.

Similar letters of reference indicate the same parts in all the figures.

A is a castiron frame surrounding the mouth of the hoistway, and A¹ is a vertical depending flange thereon lying within the latter. At opposite corners on the same side of the flange are vertical angleirons or legs A² each secured to the flange to form part thereof and may if preferred be formed integral therewith.

B B are the doors hinged to the frame at B¹ B¹ and opening upwardly as usual.

Pivotedly attached to the angle irons A² at points near the lower ends thereof, by bolts A³ in the housings A⁴, are two levers C C¹ each somewhat longer than half the distance between the centers A³ A³ and with

their free ends lapped one upon the other. The lever C¹ is slotted as at c, and the lever C carries a pin or bolt C² which extends through the slot and loosely joins the free ends of the levers, compelling them to rise and sink together, the slot c permitting the required play.

At a point C³ on each lever is a bolt D¹ serving as a pivotal connection for the lower end of a link D, preferably of angular form as shown, each pivotally joined at the upper end to the door B on the same side, by a bolt D² extending through a housing F thereon.

It is obvious that any force tending to raise either of the levers from the depressed position will correspondingly tend to raise the doors through the thrust of the links D D, and when thus elevated any force tending to depress either lever will correspondingly lower or close the doors. The levers may be thus operated by a variety of means, that shown comprises a plate G fixed upon the lever C and having an arm G¹ lying above the lever and extending parallel therewith, forming an open slot or long notch or way g adapted to receive a vertically movable member as the pin or roller H. The arm G¹ is of such length as to permit the escape of the roller in its upward travel when the levers have been moved sufficiently to open the doors fully, and to permit the roller to pass the nose of the arm on its descent and strike and thus engage the upper edge of the plate at G², initiating the downward movement of the lever, again entering the notch g and traversing it as required by the arc described by the lever in its movement. The end of the arm G¹ is curved to facilitate such engagement and disengagement of the roller.

The gravity of the doors and their attached links and levers is preferably partially counterbalanced by a vertically sliding weight J suspended by a cable J¹ running over a pulley J² mounted on the flange A¹, and attached to the lever C at the point c¹.

The roller H may be mounted on any vertically movable mechanism adapted to cause the roller to travel in a fixed vertical path or in proper relation to the plate G; as before stated, the invention is designed to serve with hoisting apparatus installed in the hoistway and arranged to be protruded through the open doors for service in hoist-

ing loads from the cellar to the sidewalk, and the roller H may be mounted on a vertically movable portion of such apparatus.

As illustrated in the drawings the invention is arranged to serve with a hoisting apparatus similar to that shown in Letters Patent to Louis O. Forman, dated April 30, 1912, No. 1,024,885, in which a hollow post K is firmly supported in the hoistway and receives telescopically a vertically movable standard L carrying at its upper end a hoisting-head in which is a hoisting-drum L¹, only partially shown, operated by a crank M through the medium of a gearwheel M¹ and pinion L² as will be understood. The standard is raised or lowered by the engagement with a rack L³ thereon of a rack-wheel K¹ operated by a crank K² through the medium of a gearwheel K³ and pinion K². This elevating mechanism is mounted on the post K which also carries guideways K⁵ K⁶ for the counterweight J. The roller H projects from a clamp H¹ securely fastened upon the standard L below the hoisting-head, or other convenient point, and is so located relatively to the notch g as to engage and coact with the lever C to open and close the doors.

It will be noted that the door operating mechanism is wholly supported upon the hatch-frame, and that the counterweight J is guided upon the post K, so that in installing the apparatus it is only necessary to erect the post in proper relation to the frame to insure correct positioning and proper operation both of the door opening mechanism and of the elevating and hoisting mechanism.

In apparatus of this character the work of raising the loads from the cellar is frequently done by a single operator, therefore it is highly advantageous to have the doors open and close automatically with the rise and descent of the hoisting-head, for the reason that it saves the several ascents to the sidewalk and return usually required in opening and closing the doors and elevating and lowering the hoisting-head.

The levers and links are in the form of thin flat bars and are located close to the frame and therefore do not obstruct the hoistway. When the doors are fully opened beyond the vertical lines of the hinges they are held open by gravity aided by the inertia and friction of the opening mechanism, and when closed are effectually locked against opening from the exterior by reason of the engagement of the roller in the notch g. The doors are practically locked when closed because the standard with its head and other connections is too heavy to be lifted by an opening pull on the doors; it requires a train of mechanism to raise the standard, and the same gearing aids in resisting the opening pull.

I claim:—

1. In a device of the character set forth, a hoistway, hoisting apparatus therein having a vertically movable standard, means for elevating said standard, vertically swinging doors covering such hoistway, means depending within the hoistway and means pivotally supported thereon and pivotally connected with each other and with said doors and coöperating with said standard for automatically operating the doors. 70

2. In a device of the character set forth, a hoistway, hoisting apparatus therein having a vertically movable standard, means for elevating said standard, vertically swinging doors covering such hoistway, means depending within the hoistway and means pivotally supported thereon and pivotally connected with each other and with said doors and coöperating with said standard for automatically operating the doors, a member rising and falling with said doors, and a coöperating member on a connection between said doors and the depending member. 80

3. In a device of the character set forth, a hoistway, vertically swinging doors covering such hoistway, levers pivoted at opposite points in such hoistway and loosely connected at their ends to rise and sink together, a link for each lever, each link pivoted at one end to the latter and at the other to one of said doors, a member in said hoistway arranged to rise and sink therein, and means on one of said levers adapted to be engaged by and coact with said member and open and close said doors. 90

4. In a device of the character set forth, a hoistway, vertically swinging doors covering such hoistway, levers pivoted at opposite points in such hoistway and loosely connected at their ends to rise and sink together, a link for each lever, each link pivoted at one end to the latter and at the other to one of said doors, a member in said hoistway arranged to rise and sink therein, means on one of said levers adapted to be engaged by and coact with said member and open and close said doors, and a weight connected to one of said levers for counterbalancing said levers, links, and doors. 105

5. In a device of the character set forth, a hoistway, vertically swinging doors covering such hoistway, levers pivoted at opposite points in such hoistway and loosely connected at their ends to rise and sink together, a link for each lever, each link pivoted to the latter at one end and at the other to one of said doors, an arm on one of said levers forming a notch, and a member in such hoistway arranged to rise and sink therein, and adapted to engage in such notch and to coact with said arm and its lever to open and close said doors. 120

6. In a device of the character set forth, a 130

- hoistway, a frame forming the mouth thereof and having a flange extending within such hoistway, swinging doors pivotally mounted in said frame and arranged to cover such hoistway, levers pivoted at opposite points on said flange and loosely connected at their ends to rise and sink together, a link for each lever, each link pivoted at one end to the latter and at the other to one of said doors, an arm on one of said levers forming a notch, and a member in such hoistway arranged to rise and sink therein and adapted to engage in said notch and to coact with said arm and its lever to open and close said doors. 45
- 5 7. In a device of the character set forth, a hoistway, a frame forming the mouth thereof and having a flange extending within such hoistway, swinging doors pivotally mounted in said frame and arranged to cover such hoistway, levers pivoted at opposite points on said flange and loosely connected at their ends to rise and sink together, a link for each lever, each link pivoted at one end to the latter and at the other to one of said doors, an arm on one of said levers forming a notch, a member in such hoistway arranged to rise and sink therein and adapted to engage in said notch and to coact with said arm and its lever to open and close said doors, a pulley on said flange, a cable thereon attached at one end to one of said levers, and a counterweight suspended from the other end of said cable. 60
- 10 8. In a device of the character set forth, a hoistway, a frame forming the mouth thereof and having a flange extending within such hoistway, swinging doors pivotally mounted on said frame and arranged to cover such hoistway, levers pivoted at opposite points on said flange and loosely connected at their ends to rise and sink together, a link for each lever, each link pivoted at one end to the latter and at the other to one of said doors, an arm on one of said levers forming a notch, a tubular post fixed in said hoistway, a vertical standard arranged to slide telescopically in said post, means carried by said post for raising and lowering said standard, and a projecting roller carried by said standard and adapted to engage in said notch and to coact with said arm and its lever to open and close said doors by the rising and sinking movements of said standard. 65
- 15 9. In a device of the character set forth, a hoistway, a frame forming the mouth thereof and having a flange extending within such hoistway, swinging doors pivotally mounted on said frame and arranged to cover such hoistway, levers pivoted at opposite points on said flange and loosely connected at their ends to rise and sink together, a link for each lever, each link pivoted at one end to the latter and at the other to one of said doors, an arm on one of said levers forming a notch, a tubular post fixed in said hoistway, a vertical standard arranged to slide telescopically in said post, means carried by said post for raising and lowering said standard, a projecting roller carried by said standard and adapted to engage in said notch and to coact with said arm and its lever to open and close said doors by the rising and sinking movements of said standard, a pulley on said flange, a cable thereon attached at one end to said notched lever, a counterweight suspended from the other end of said cable, and guideways for said weight carried by said post. 70
- 20 10. In testimony that I claim the invention above set forth I affix my signature, in presence of two witnesses. 75
